UNITED STATES PATENT OFFICE.

ROBERT FRIEDRICH BAERLOCHER, OF BRIGHTON, ENGLAND.

MEANS FOR OPERATING LIQUID ELECTRIC CONTROLLERS AND STARTERS.

1,101,050.

Specification of Letters Patent. Patented June 23, 1914.

Application filed November 12, 1913. Serial No. 800,552.

To all whom it may concern:

Be it known that I, ROBERT F. BAERLOCHER, residing at Brighton, Sussex, England, have invented certain new and useful 5 Improvements in Means for Operating Liquid Electric Controllers and Starters; and I do hereby declare the following to be a full, clear, and exact description of the invention, such as will enable others skilled in 10 the art to which it appertains to make and use the same.

This invention relates to liquid electric controllers and starters, and its object is to provide a reliable means for operating liquid controllers and starters so that the time taken in starting and accelerating the motor is automatically limited and independent of the speed of operating the starting lever. This protection is often necessary, especially 15 in the case of large three phase motors for winders where, if the time of starting and accelerating is left to the operator, there is a danger of too quick a start and uneven acceleration. Hitherto this protection against 20 25 too quick and uneven acceleration has been effected by pumping the resistance liquid continuously into a tank containing fixed electrodes; these electrodes being so arranged that the rising liquid gradually decreases the resistance in the motor circuit; the level of the liquid being regulated by a gate valve or sluice, and the time of filling the tank being limited by the capacity or adjustment of the pump.

30 35 40 45 50 In carrying out the present invention I use controllers with moving electrodes in place of fixed ones, and the resistance in circuit is varied by their movement instead of making use of rising and falling resistance liquid. The electrodes tend to move by gravity to the "full on" or short circuiting position, but they are balanced by a weight which in air is sufficiently heavy to return them to the "off" position, in which all the liquid resistance is in circuit. When this balance weight is partly or wholly submerged in water, its effective weight is not sufficient to balance the electrodes. Thus I can control the position of the electrodes by suspending the balance weight in a tank

alongside the controller, and providing means to vary the depth of water in this tank. The manner of effecting this variation of the depth of water in the tank will depend on whether or not there is a continuous 55 water supply available.

The method of carrying out the invention is illustrated by the accompanying drawings, in which:

Figure 1 is a part sectional elevation of 60 the apparatus, as adapted for use in places where a continuous supply of water is available. Fig. 2 is a sectional elevation of the apparatus as adapted for use where no continuous water supply is available. Fig. 3 65 shows modified form of water level control device.

Referring to Fig. 1, the electrodes are contained in the tank 1, and can be raised from or lowered into the said tank by means of 70 the chain 2 passing over the pulleys 3, and being attached to a rod 2^a, carrying the electrodes. The chain 2 passes through a hole in the cover of a second tank 4, and carries within this tank 4 a weight 5, which can 75 move freely within said tank, thereby raising or lowering the electrodes in the tank 1. This weight operates by gravity in such manner that when the tank 4 is empty, the weight falls and raises the electrodes in the 80 tank 1. Water can be run into the tank 4 through the pipe 6 and the valve 7, communicating with the reservoir 8, which is filled from the main by means of the pipe 9, and 85 the ball valve 10. The tank can be emptied by means of the sector or like valve 11, which in the position shown in the drawing is open to let the water run out to a waste pipe, gully, sink or the like. The inlet 90 valve 7 and the outlet valve 11 are connected by levers 12, so as to operate in harmony in such manner that when the one is open the other is shut, and vice versa, and both the valves are operated from the starting lever 13 by means of the link 14. The tank 1 containing the electrolyte is water cooled as indicated by the cooling water inlet 15 and overflow pipe 16, and by means of the three way tap 17, the overflow water from the 100

cooling tubes in the tank 1 can either be run to waste or into the tank 4. A stop cock 18 for turning off the water supply from the reservoir 8 is also provided, this cock is also used for regulating the speed of operation. The wiring of the motor circuit is so arranged that when the electrodes are in the full "on" position no resistance is in circuit, but when the former are raised to the "off" position, the whole of the liquid resistance is in circuit.

Fig. 2 shows the same device as adapted for use in places where no continuous supply of water is available, and in this case the invention is shown with three liquid resistances and three electrodes, for use with three phase current electric control. The arrangement for raising and lowering the electrodes into the electrolyte are substantially the same as in the previous case, the difference being in the arrangement of the tank containing the counterpoising weight, and in the manner of raising and lowering the same. In this case, the tank 4 (Fig. 2) is so constructed that it contains an upper chamber 19, formed by the partition 20, and the weight 5', attached by means of chain 2, and pulleys 3, and rods 2^a, as in the previous case to the electrode or electrodes 21, can move freely either up or down in the said chamber 19. The lower part of the tank 4' is filled with water, and from this stock of water, a portion can be pumped into the upper chamber 19, so as to raise the weight 5', by means of the centrifugal pump 22, and pipe 23. The pump 22 may be driven electrically or in any other convenient manner, the motor switch in this case being linked to the starting handle, or the pump may continuously operate, the water returning to the lower tank either over the partition 20 or through the valve 11'. The pump in this case may also cause circulation within the cooling system. The cooling pipes, for cooling the liquid resistance are shown in Fig. 2 at 15 and 16, while the motor and its wiring are indicated at 25.

The operation of the device is as follows:—When it is desired to start the motor, water is caused to rise in the chamber containing the balance weight, by either of the two devices above described. This causes the effective weight of the said balance weight to decrease, and it is then no longer able to hold the electrodes in the "off" position. The weight therefore rises and the electrodes descend in the electrolyte. By regulating the flow of water causing the weight to rise, the speed of starting the motor can be regulated, the resistance in circuit will diminish as the electrode descends in the electrolyte. When the motor has been stopped, the water is run out

of the tank containing the weight, which thus falls and raises the electrodes and again inserts the resistance in circuit.

In Fig. 3 an alternative method of water level control device is shown. In this device an outlet pipe 30 is hinged by means of a flanged elbow 31 which admits of the said pipe having angular motion, a collar 32 retaining said elbow *in situ*, a link 33 is connected to said pipe and is hinged therewith on pin 34, said pin forming part of adjustable pipe collar 35. To operate the device the pipe is lowered through link 33, when its angle determines the height of the fluid in the operating tank, which therefore determines the speed of the motor. A cock 36 allows the device to be placed out of operative condition. The following are among the advantages of this method of construction and operation; firstly the electrolyte is not pumped; secondly no pump is required where a water service is available. Where no water service is available a much smaller pump can be used, as only sufficient water is needed to displace the unbalanced weight; and thirdly the controller occupies less space and can be taken below ground if required in an ordinary pit cage.

I claim:—

1. The combination, with an electric controller and starter, for an electric motor, having a movable electrode and an electrolyte of substantially constant level; of means for automatically controlling the speed actuation of the said controller and starter substantially independently of the speed of operating the starting device.

2. The combination, with an electric controller and starter, for an electric motor, having a movable electrode and an electrolyte of substantially constant level; of a hydraulic regulator operatively connected with the said electrode, and means for varying the supply of liquid to the hydraulic regulator, whereby the movements of the electrode in the electrolyte are controlled automatically.

3. The combination, with an electric controller and starter, for an electric motor, having a movable electrode and an electrolyte of substantially constant level; of a hydraulic cylinder, a weight operatively connected with the electrode and suspended in the said cylinder, and means for admitting liquid to and discharging liquid from the said cylinder at will to permit the weight to operate the electrode automatically.

4. The combination, with an electric controller and starter, for an electric motor, having a movable electrode and an electrolyte of substantially constant level; of a hy-

draulic cylinder and a tank for liquid operatively connected together, a weight operatively connected with the electrode and suspended in the said cylinder, means for discharging liquid from the cylinder into the tank, and means for forcing liquid from the said tank into the said cylinder, so that the same liquid is used repeatedly to permit

the weight to operate the electrode automatically.

In testimony whereof I have affixed my signature, in presence of two witnesses.

ROBERT FRIEDRICH BAERLOCHER.
